UNITED STATES PATENT OFFICE.

ALPHONSE FERNANDEZ, OF WASHINGTON, DISTRICT OF COLUMBIA.

MINE-DESTROYING DEVICE.

1,235,783.

Specification of Letters Patent. Patented Aug. 7, 1917.

Application filed September 20, 1916. Serial No. 121,252.

To all whom it may concern:

Be it known that I, ALPHONSE FERNANDEZ, a subject of the King of Spain, residing at the city of Washington, in the District 5 of Columbia, have invented certain new and useful Improvements in Mine-Destroying Devices; and I do declare the following to be a full, clear, and exact description of the invention, such as will enable others skilled 10 in the art to which it appertains to make and use the same.

My invention has for its object to provide an efficient spring actuated gun for use on submarines for the purpose of secretly directing projectiles against mines while the 15 vessel is submerged. In carrying out this object, I employ certain novel features of construction and unique combinations of parts to be hereinafter fully described and 20 claimed, the descriptive matter being supplemented by the accompanying drawings which constitute a part of this application and in which:

Figure 1 is a side elevation of the improved gun showing the same located in an external compartment of a submarine, the device being in position for loading;

Fig. 2 is a similar view after a projectile has been placed in the barrel;

Fig. 3 is a central vertical longitudinal section;

Fig. 4 is a top plan view;

Fig. 5 is a horizontal section showing the relation of parts when the projectile is first 35 placed in the barrel;

Fig. 6 is a similar view with the projecting spring compressed;

Figs. 7 and 8 are transverse sections on the planes indicated by the line 7—7 of 40 Fig. 4, showing different positions of parts; and

Fig. 9 is a detail longitudinal section on the plane indicated by the line 9—9 of Fig. 4.

In the drawings above briefly described, the numeral 1 designates an external compartment in a submarine, said compartment being water tight but having doors 2 which may be opened so that the improved gun 50 which is mounted in said compartment 1 may direct projectiles against so-called floating mines, another door 3 being provided for the purpose of permitting gunners in diving suits to enter the compartment 1, the 55 diving suits employed preferably having individual air tanks although air may be sup-

plied to the men from the interior of the ship by the provision of other suitable means. These details, however, need not be entered into at length in the present application.

A suitable base 4 is mounted on the bottom of the compartment 1 and a rotary gun mount 5 is disposed on said base, the gun barrel 6 being pivoted at 7 to said mount to 60 permit it to swing vertically. The barrel 6 is open at its rear end to permit the insertion of metal projectiles 8 and any appropriate type of trigger 9 is provided for holding the projectiles against forward 65 movement until the required time, the trigger 9 being shown in the form of a vertical bolt having an operating lever 10 by means of which it may be released.

A stiff coiled spring 11 is adapted to be 70 inserted in the rear end of the barrel 6 and to be compressed against the projectile 8, said spring being carried by a cross head 12 whose ends are formed with bearing 75 openings through which a pair of screws 13 pass rotatably, said screws being formed of front and rear sections 14 and 15 hinged together at 16, the front sections 14 carrying the screws proper which pass slidably 80 through ears 17 which rise from flanges 18 85 on the opposite sides of the barrel 6, the outer edges of said flanges preferably having channels 19 which receive the screws slidably (see Figs. 7, 8 and 9).

Semi-cylindrical nuts 20 are pivoted at 90 21 to the flanges 18 in such a manner as to permit them to swing vertically, said nuts when lowered engaging the screws 13 whereby as the latter are turned they will move the cross head 12 inwardly to compress the 95 spring 11 preparatory to releasing the trigger 9 to cause said spring to impel the projectile 8 toward the mine, at which the gun is pointed. To quickly return the cross head 8 and the spring 11, however, for reloading 100 the gun, the nuts 20 are swung upwardly to the position shown in Fig. 8 and thus a rearward pull on the cross head will move the numerous parts to normal position, the 105 hinges 16 permitting the rear sections 15 of the screws 13 to swing downwardly as shown in Fig. 1 for the purpose of allowing another projectile to be uninterruptedly inserted in the barrel.

Any suitable means may be provided for 110 raising and lowering the nuts 20 but they are preferably connected by links 22 with

points on opposite sides of the fulcrum of a lever 23 mounted on top of the barrel 1, a suitable pawl 24 and rack 25 being employed for locking the lever 23 in one position or the other.

The unthreaded portions of the screws 13 pass slidably through guides 26 on the rear end of the barrel 6 and thus when the cross head 12 is lifted from the position shown 10 in Fig. 1 and forced forwardly, the hinges 16 will be received in said guides to sustain the sections 15 of the screws, thus relieving the weight thereof from the spring 11.

For turning both screws 13 simultaneously, any suitable means may be provided but the rear ends of said screws are preferably equipped with gears 27 meshing with another gear 28 which is equipped with a handle 29.

20 In use, the submarine equipped with one or more of the improved guns will travel a suitable distance below the surface of the water to permit the mines to be located. By means of a telescopic sight such as that 25 indicated at 30, the gun will now be aimed at the target by the divers within the compartment 1 the doors 2 having been previously opened. By operating the lever 10 a projectile may now be forced from the gun 30 against the mine to explode the latter and this having been done, the lever 23 is operated to raise the nuts 20. This allows the cross head 12 to be moved rearwardly to withdraw the spring 11, whereupon said 35 head is lowered and another projectile is inserted in the breech of the barrel. When the cross head 12 is now again raised and forced forwardly, the nuts 20 are shifted downwardly into engagement with the 40 screws 13 whereupon turning of the gear 28 by the handle 29 will cause the screws to pull the cross head inwardly to again compress the spring 11 for discharging the second projectile. All subsequent operations 45 will be performed in the same manner and it will be obvious that the device is an effective instrument of naval warfare.

On account of ease of operation and the advantages derived, the construction shown 50 and described constitutes the preferred form of the device but it is to be understood that within the scope of the invention as claimed, numerous changes may be made without sacrificing the principal advantages.

I claim:

1. A gun of the class described comprising a barrel having an open rear end into which projectiles are to be placed, a trigger for temporarily holding the projectile in place in said barrel, a spring to be inserted into 60 the barrel in rear of the projectile, a support on which said spring is carried, and means for moving said support forwardly to compress the spring and for permitting said support to be quickly retracted to withdraw the spring after the trigger is released.

65 2. A gun of the class described comprising a barrel having an open rear end into which projectiles are to be placed, a trigger for temporarily holding the projectile in 70 place in said barrel, a spring to be inserted into the barrel in rear of the projectile, a support on which said spring is carried, a screw for moving the support forwardly to compress the spring, a support for said 75 screw, and a half nut movable downwardly onto said screw, said nut when raised from engagement with the screw permitting quick retraction of the latter.

80 3. A gun of the class described comprising a barrel open at its rear end to receive a projectile, a trigger for temporarily holding the projectile against forward movement in the barrel, a support carrying said spring, a screw for compressing said spring, said 85 screw having one end mounted on said support and being formed of two sections hinged together to permit the spring to move downwardly below the barrel, and a guide into which the hinge may be moved to sustain the rear section of the screw.

90 4. A gun of the class described comprising a barrel open at its rear end to receive a projectile, a trigger for temporarily holding said projectile against forward movement in the barrel, a coiled spring insertible into said rear end of the barrel, means for compressing said spring against the projectile, and means for then releasing said trigger.

95 100 In testimony whereof I have hereunto set my hand in the presence of two subscribing witnesses.

ALPHONSE FERNANDEZ.
